UNITED STATES PATENT OFFICE.

ELISHA EMMANUEL STRONG, OF PARIS, FRANCE, ASSIGNOR TO UNDERWOOD TYPE-WRITING COMPANY, OF NEW YORK, N. Y., A CORPORATION OF DELAWARE.

TYPE-WRITING MACHINE.

1,106,424.

Specification of Letters Patent. Patented Aug. 11, 1914.

Application filed May 1, 1913. Serial No. 764,754.

To all whom it may concern:

Be it known that I, ELISHA EMMANUEL STRONG, a citizen of the United States, residing in the city of Paris, Republic of France, have invented certain new and useful Improvements in Type-Writing Machines, of which the following is a specification.

The primary object of my invention is to provide in a typewriting machine, signal mechanism which will operate a bell or other signal device when the line-space lever has been operated a pre-determined number of times after a work sheet has been placed in the machine, thereby notifying the operator that the work sheet has been filled, or that any pre-determined bottom margin limit has been reached.

In various makes of typewriting machines, including the front-strike type of Underwood machine to which the present invention as shown is particularly adapted, the lower edge of the paper is hidden from view and it is difficult to determine the width of the bottom margin without some form of indicating device for this special purpose. By means of the present invention, the bell is rung automatically by the operation of the line-space lever; so that the operator's attention is arrested, and the pre-determined margin limit is therefore not passed accidentally.

A rack bar is slidably mounted on the front rail of the carriage, and is adapted to be moved longitudinally of the carriage step by step by means of a dog actuated by the line-space lever. This dog has a tooth to engage the rack and move it forward, and also means for withdrawing a holding detent in engagement with the rack bar. Said detent is mounted on a lever having an arm projecting forwardly over a ledge on the usual oscillating bar which controls the bell. When the rack bar has been fed beyond said detent, the latter is permitted to swing forwardly and operate the said oscillating bar to ring the bell. This takes place when the line-space lever is operated to position the platen for the last line on the sheet. Before commencing a new sheet the rack bar is returned by hand to starting position. A stop adjustable along the rack bar deter-

mines the number of operations of the line-space lever required to bring the device to signal position.

Other objects of the invention will appear hereinafter.

In the accompanying drawings, Figure 1 is a perspective view from a point in rear of the left-hand end of the machine, showing an Underwood typewriting machine with my invention applied thereto. Fig. 2 is a front perspective view of a signal controlling and operating mechanism. Figs. 3 and 4 are rear elevation views of the same, Fig. 3 showing the parts in their normal position of rest, and Fig. 4 showing the position of parts assumed when the forward movement of the line-space lever has been completed and before its return. Figs. 5 and 6 are sectional elevation views of the parts in positions indicated in Figs. 3 and 4 respectively. Fig. 7 is a similar view showing the position of parts when the rack has passed beyond the detent and the bell is being rung. Fig. 8 is a detail view of the rack.

A rotatable platen 1 is journaled in the ends 3 and 4 of a platen frame, which also comprises a paper shelf 5 connecting the ends of the frame, said frame being shiftable up and down in the traveling carriage frame. A roller 7, mounted on the front rail 6 of the carriage frame, travels on a horizontal rod 8 secured in the stationary frame 9 of the machine. The carriage is also supported and guided on a stationary rail 10.

The line-space mechanism comprises a bell crank lever 11 pivoted at 12 and having an arm 13 which actuates a slide bar 14 to which is pivoted a dog 15 having a tooth 16 to engage a line-space wheel 17 secured to the platen axle. A returning spring 14' is connected to the slide bar 14 and platen frame. A spring-pressed detent 18 holds the platen in operated position. The usual right and left-hand margin stops are provided. A stop 20, controlling the left-hand margin of the work sheet is slidably mounted on the rod 8 and a parallel rod 21. Pivoted to the stop 20 is a dog 22 adjustably held by rack teeth 23 formed on the rod 8. The dog 22 may be lifted from its rack by means of a finger piece 24 to permit adjustment of the stop.

The right-hand margin of the work sheet is controlled by a stop 23 slidably mounted on the rod 21 and carrying a dog which cooperates with rack teeth 26 formed on a bar 27, the dog being releasable by means of a finger piece 28 to permit adjustment of the stop. The bar 27 is provided at its ends with forwardly-extending ears 29 journaled on the rod 21, whereby the bar 27 is permitted to oscillate about the rod 21 as a fulcrum. A depending arm 30, secured to the rack bar 27, carries at its lower end a pivoted wiper 31 which works on a cam surface 32 of a lever 33, carrying a hammer 34 of a bell 35. Projecting forwardly from the front rail 6 of the carriage frame is an arm 36 adapted to strike a cam 37 carried by the stop 23, thereby depressing the bar 27 which swings the arm 30 forwardly and rings the bell. The rack bar 27 may be returned by a spring 38. The parts thus far described may be of usual construction as found in the commercial Underwood typewriting machine.

The gage controlling the automatic signal 25 at the completion of the writing of a work sheet, comprises a rack bar 40 slidably mounted on the front rail of the carriage. This rack bar has substantially the shape of an I-beam in cross section and comprises an upper horizontal flange 41 and a lower horizontal flange 42 connected by a vertical web 43. The rear extension on the flange 41 has cut-away portions to form a series of ratchet teeth 44. Rack teeth 45 are likewise formed 30 on the rear extension of the lower flange 42. Depending rack teeth 46 are also formed on the lower flange. The rack is guided between the carriage rail 6 and a vertically-disposed plate 47 secured to the rear face 10 of said rail. Said plate is formed at its upper edge with a flange overhanging the lower flange of the rack bar. Guide plates 48 secured to the upper face of the rail 6 also overhang the lower flange 42 of the 15 rack bar. The plate 47 is formed with depending and forwardly-projecting arms 49 in which are threaded pivot bolts 50 having conical ends forming adjustable cone bearings for a detent lever 51. A detent roller 52 carried by said lever seats between the rack teeth 45 to hold the rack bar. The detent is held in position by a spring 53.

The rack bar is moved forwardly by means of an operating dog or lever 54 slidably and 55 pivotally mounted on the carriage rail 6 by means of a screw 55 extending through a slot 56 in the lever and threaded into the rail 6. The longitudinal movement of the lever 54 is limited by stops 57 and 58, adjustably secured to the lever by screws 59 and 60 respectively, extending through slots in said stops and threaded into the lever. A limited pivotal movement of the lever is provided by a widened slot 61, through which extends a

stop screw 62 threaded into the carriage rail 6. A stop 50 on the dog 54 is adapted to rest on the arm 49 and limit the downward movement of the end of the dog.

Secured to the line-space lever 11 is an arm 63 which, when the line-space lever is actuated, strikes a cam 64 on the depending end of the lever 54. The movement of the arm 63 is in a horizontal direction and when it strikes the cam surface 64 it swings the dog 54 about its pivot and brings a tooth 65 on the end of the dog upward against the rack 46. A spring 66 connected at its ends to the pivoted dog and carriage frame, has sufficient tension to prevent endwise movement of the dog while it is being swung up to engage the rack bar. After this swinging movement of the dog, the continued movement of the arm 63 carries the dog and rack bar forward the distance between two adjacent teeth 46, when the movement is arrested by the lever 11 striking a stop 67. The parts are thus brought to the position shown in Fig. 4. During the forward movement of the dog a finger 68 thereon engages behind the detent roller 52 or an anti-friction roller 69 below said detent roller, and cams the latter outwardly to permit a free movement of the rack. When the line-space lever 11 is released, the dog 54 is returned by the spring 66 into position to engage the next succeeding tooth of the rack bar when again operated. In this manner the rack bar is fed forwardly one step at each operation of the line-space lever until the rack teeth 45 pass beyond the detent 52. When this takes place the detent is carried inwardly to the position shown in Fig. 7 whereby a tail 70 of the detent lever is caused to strike a rearwardly projecting ledge or flange 71 on the rack bar 27 and swing the latter downward to operate the bell. The ledge 71 may be a separate bar secured to the rack bar 27 by screws 72.

An adjustable stop on the bar 40 comprises a spring-operated latch 73 having a nose 74 to enter between any two adjacent teeth 44 of the rack and hold the stop in adjusted position. A fixed stop 75 formed by a projection of the plate 47 lies in the path of the adjustable stop. A vertical flange 76 on the adjustable stop forms a finger piece for returning the rack at the time the work sheet is placed in the machine. The adjustable stop is placed at a distance from the left-hand end of the rack (Fig. 2) corresponding to the number of lines it is desired to write on the work sheet. When the latter is placed in the machine, the rack bar is moved to the left to bring the stop thereon against the fixed stop 75.

As the paper is fed forward through the machine by the operation of the line-space lever, the rack 40 is moved to the right and

at the completion of the writing on the work sheet automatically rings the bell, as hereinbefore explained. When a different sized sheet is placed in the machine, or if it is desired to vary the width of the lower margin, the stop is adjusted along the rack, the direction and the distance corresponding to the desired change in the number of lines. The rack bar is preferably provided with scale markings 77 to assist in quickly and accurately adjusting the stop. A finger piece 78 on the detent lever 51 provides a convenient means for operating said lever by hand.

15 When it is not desired to use the signal device, the adjustable stop is moved to the right-hand end of the rack bar (Fig. 2) and the latch 73 is engaged in a notch 79. The rack bar is then moved to the left to bring 20 the fixed and movable stops together. In such position, the detent lever 51 is held up so that it will not interfere with the oscillation of the rack bar 27 in the usual way to give a signal at the end of each line of 25 writing. The line-space lever cannot now operate the rack because the tooth 65 of the operating dog is beyond the end of the rack 46.

Variations may be resorted to within the 30 scope of the invention, and portions of the improvements may be used without others:

Having thus described my invention, I claim:

1. In a typewriting machine, the combination with a carriage and a line-space mechanism thereon, of a signal device upon the machine frame, and a train of mechanism operated by the line-space mechanism and including parts on the carriage, to activate the signal on the machine frame after a pre-determined number of operations of said mechanism.

2. In a typewriting machine, the combination of a signal device, means to operate said device as each line of writing nears completion, and additional means causing said device to operate automatically after a pre-determined number of lines have been written.

50 3. In a typewriting machine, the combination with a traveling carriage and a rotary platen thereon, of a signal automatically operated by the travel of the carriage, mechanism to rotate the platen, and means controlled by said mechanism to operate the signal.

4. In a typewriting machine, the combination with a traveling carriage and a rotary platen carried thereby, of a signal automatically operated when the carriage reaches a pre-determined position in its travel, platen-rotating mechanism, and means causing said signal to operate automatically after a pre-determined rotation of the platen.

5. In a typewriting machine, the combination with a carriage and a line-spacer thereon, of a signal upon the machine frame, and a signal-controlling train mounted partly on the carriage and extending to the signal, said train including a device to which a step-by-step movement is imparted by the operation of the line-spacer to actuate the signal on the machine frame after a pre-determined number of operations of the line-spacer.

6. In a typewriting machine, the combination with a traveling carriage and a rotary platen, of a manual device for rotating the platen and returning the carriage after each line or part of a line has been written, an alarm upon the machine frame, and means mounted partly on the carriage and actuated by said manual device and extending to the alarm to actuate the same after a pre-determined number of operations of said device.

7. In a typewriting machine, the combination with a carriage and a line-space lever thereon, of a train of mechanism mounted partly on the carriage and including a rack, a dog actuated by said lever to move the rack, and a signal device on the frame controlled by the movement of predetermined extent of said rack.

8. In a typewriting machine, the combination with a carriage and a line-space lever thereon, of a train of mechanism mounted partly on the carriage and including a rack, a pivoted dog operated by said lever to impart a step-by-step movement to the rack as the lever is repeatedly operated, and a signal device on the frame controlled by said rack and actuated when the rack has been moved a pre-determined distance.

9. In a typewriting machine, the combination with a traveling carriage, of a rotary platen thereon, a line-space mechanism comprising a lever, a rack slidable variable distances on the carriage frame, a dog actuated by said lever to feed the rack forward each time the lever is actuated, an alarm on the frame, and means controlled by said rack within the space of its sliding movement and extending to the alarm on the frame, to operate said alarm at the termination of the movement of the rack.

10. In a typewriting machine, the combination with a carriage, of a line-space lever, a rack mounted on the carriage, and slidable variable distances thereon, a dog connected to the carriage for pivotal and longitudinal movement, means operated by the line-space lever at each line-spacing movement thereof to first swing the dog on its pivot and move a tooth thereon into engagement with the rack, and by the further movement of the lever move the rack forward, an alarm device on the frame, and means extending to said alarm device from

said rack and whereby it is caused to operate automatically after the rack has been moved a pre-determined distance.

11. In a typewriting machine, the combination with a carriage, of a rack slidable thereon, a dog connected to the carriage frame for pivotal and longitudinal movement, a line-space lever, an arm connected thereto and movable in each line-spacing movement of said lever to engage a cam on the said dog and impart a pivotal movement thereto to connect the dog with said rack, and by the further movement of said arm to move the dog and rack bodily forward, and a signal device controlled by said rack.

12. In a typewriting machine, the combination with a traveling carriage, of a rack slidably mounted thereon, a line-space mechanism, operating connections between said mechanism and the rack for imparting a step-by-step movement to the rack, a stop adjustable to determine the initial position of the rack, and means mounted partly on the carriage and extending to a signal on the machine frame, said means controlled by said rack for operating said signal after a number of operations of the line-space mechanism determined by the adjustment of said stop.

13. In a typewriting machine, the combination with a traveling carriage, of an oscillating rack bar, a stop adjustable along said rack bar, a signal device operated by the oscillation of said rack bar, a cam carried by said rack bar in the path of an arm on the carriage for operating the signal when the carriage reaches a pre-determined position in its travel, a line-space mechanism, and a device controlled and operated thereby for oscillating said rack bar and operating the signal.

14. In a typewriting machine, the combination with a traveling carriage and a rotary platen thereon, of an oscillating bar on the machine frame, means to oscillate said bar at a given position in the travel of the carriage, a line space mechanism, means operated thereby to oscillate the said bar, and a signal device actuated by the oscillation of said bar.

15. In a typewriting machine, the combination with a traveling carriage, of a rack slidable thereon, a detent lever, a detent carried thereby to engage between teeth on the rack, a line-space lever, a dog actuated thereby to feed the rack, and an alarm device controlled by the detent lever and actuated by said lever when the rack has been fed forward to a position to release the detent.

16. In a typewriting machine, the combination with a rack bar, of a line-space lever, a dog actuated by said lever to feed the rack bar, a detent to engage between teeth on the

rack bar, means on said dog to cam the detent outwardly and permit the feeding of the rack bar, and an alarm device controlled by said detent.

17. In a typewriting machine, the combination with a traveling carriage, of a rocking member pivoted in the machine frame and extending longitudinally of the carriage, a signal device operated by said rocking member, a detent lever pivoted to the carriage and extending into position to rock said member, a rack slidable on the carriage frame for holding said detent lever inoperative, a line-space lever, and means operated thereby to move the rack and release the detent.

18. In a typewriting machine, the combination with a carriage frame, of a rack bar slidable thereon and formed with two series of rack teeth, a line-space lever, a dog operated thereby to engage one series of rack teeth and operate the rack, a detent engaging the other series of rack teeth, and a signal device controlled by said detent.

19. A signal device mounted on the frame of a typewriting machine having a traveling carriage, a line-spacing mechanism, and means partly mounted on said carriage and extending to said signal device for operating the latter by said line-spacing mechanism in various positions of the carriage.

20. In a typewriting machine having a carriage, the combination with a line-space mechanism for said carriage, of a signal device upon the machine frame, and actuating means therefor mounted in part upon the carriage and extending to said signal device, said means operated by said line-space mechanism at various positions of said carriage to cause the actuation of said signal device after a predetermined number of line-spacing operations.

21. In a typewriting machine having a signal device mounted upon its frame, the combination of a carriage, line-spacing mechanism therefor, and means mounted in part on said carriage and extending to said signal device, said means controlled by said mechanism for causing the operation of said signal device in various positions of said carriage.

22. A signal device for typewriting machines having operating means controlled by the carriage in its letter-feeding movement, and independently controlled by the line-spacing mechanism.

23. A signal device for typewriting machines having operating means controlled by the carriage in its letter-feeding movement, and independently controlled by the line-spacing mechanism, and adjustable means for determining the line at which the signal device will operate.

24. A signal device mounted on the frame

of a typewriting machine having a traveling carriage, means for operating said signal device near the end of the carriage movement, a line-spacing mechanism, and means for operating said signal device by said mechanism in various positions of the carriage.

25. In a typewriting machine having a traveling carriage and a line-space mechanism therefor, the combination of a signal

device operable by said carriage near the end of its line movement, and means whereby said line-space mechanism causes the operation of said signal device after a predetermined number of line-spacing operations. 15
